UNITED STATES PATENT OFFICE.

HEINRICH SPECKETER AND EDUARD MARBURG, OF GRIESHEIM-ON-THE-MAIN, GERMANY, ASSIGNEES TO CHEMISCHE FABRIK GRIESHEIM-ELEKTRON, OF FRANKFORT-ON-THE-MAIN, GERMANY, A CORPORATION OF GERMANY.

MANUFACTURE OF REDUCTION PRODUCTS OF SULFUROUS ACIDS AND SALTS THEREOF.

1,169,365.

Specification of Letters Patent.

Patented Jan. 25, 1916.

No Drawing.

Application filed February 2, 1914. Serial No. 316,063.

To all whom it may concern:

Be it known that we, HEINRICH SPECKETER and EDUARD MARBURG, both subjects of the German Emperor, and resident of Griesheim-on-the-Main, Germany, have invented certain new and useful Improvements in Connection with the Manufacture of Reduction Products of Sulfurous Acid and Salts Thereof, of which the following is a specification.

In the manufacture of reduction products of sulfurous acid and its salts by means of zinc as reducing agent the zinc has been hitherto used in the form of zinc dust. We have found that the use in such processes of spongy metallic zinc obtained by electrolysis presents great advantages over the use of zinc dust. For instance, in the manufacture of hydrosulfite solutions using the said spongy zinc and water and sulfurous acid, the formation takes place much more energetically than it does when zinc dust is employed and the use of spongy zinc in addition to thus enabling the operation to be carried on much more expeditiously than hitherto, presents the further advantage that even with the more rapid supply of sulfurous acid, excessive acidity and decomposition of the solution of hydrosulfite do not occur.

As spongy zinc can be very easily obtained from zinc oxid, zinc hydroxid, zinc carbonate, or waste containing oxidizable zinc, and as the oxidized waste resulting from the reduction process can be readily regenerated, spongy zinc is not only much cheaper than zinc dust but has also the advantage that in consequence of its easy recuperation the process can be conducted with a minimum of zinc and the industrial carrying out of the reduction process is not only simplified and expedited by the employment of spongy zinc but it is also considerably cheapened, and this is of great importance in the manufacture of reduction products of sulfurous acid, because the price of zinc dust has formed a large item of the total cost of production, even taking into account value of the resulting residues containing zinc oxid.

The fact that, although spongy zinc obtained by electrolysis has been long known it has not been used in place of zinc dust for the production of reduction products of sul-

furous acid, and salts thereof may be accounted for by the fact that no industrial advantage was foreseen, and it was supposed that spongy zinc would not be sufficiently durable.

In the production of aldehyde sulfoxylate spongy zinc possesses another important, and hitherto unknown property for the purpose of the reduction. We have found that, by starting from a ready-made alkali-bisulfite-formaldehyde, or from a formaldehyde-sulfite mixture such as hydrosulfite-formaldehyde, *i. e.* a mixture or double salt of bisulfite-formaldehyde and formaldehyde-sulfoxylate, it is possible to readily obtain, without any further addition, an excellent yield of formaldehyde-sulfoxylates, if spongy zinc obtained by electrolysis be used as reducing agent. The yield is in this case about 85 to 90 per cent. Hitherto it has not been possible to carry out successfully the direct production of the formaldehyde-sulfoxylates by reduction of the ready made alkali-bisulfite formaldehydes or hydrosulfite-formaldehydes by means of zinc dust without the use of considerable quantities of an addition for insuring the favorable run of the reaction. For instance in accordance with the specification of German Patent No. 165,807 an addition of acid (for instance acetic acid) is needed. In accordance with the specification of German Patent No. 222,195, the desired effect is obtained by the addition of zinc-, or ammonium-sulfite, or -bisulfite, or by the addition of the zinc-, or ammonium-salts of formaldehyde-sulfurous acid, or of formaldehyde-hydrosulfurous acid.

In accordance with the examples given in that specification the components are to be added in quantity equivalent, or nearly equivalent, to the bisulfite formaldehyde used, and not in accordance with the theoretical consideration set forth on page 1, lines 22 to 57, of the said specification, according to which the addition of quite a small amount of zinc salt would suffice to reduce large amounts of bisulfite-formaldehyde. In accordance with the specification of German Patent No. 256,460, the addition chosen to promote the reduction is zinc oxid, zinc hydroxid, or zinc carbonate, more than 60 per cent. of the full equivalent of zinc oxid being added. The same object, namely

the avoidance of an addition of acid and the consequent production of the zinc and alkali salts of this acid, is attained in the process in accordance with the specification 5 of German Patent No. 202,242, in which it is proposed to cause sodium bisulfite, formaldehyde and zinc dust to react on one another at a full boiling heat. In this case too, the addition which is essential for the reaction 10 is the suitably chosen excess of free sodium bisulfite, starting from the ready formed bisulfite-formaldehyde, being expressly avoided.

As zinc-dust itself is a very energetic and 15 finely dividing reducing agent, it was not to be foreseen that by using electrolytically prepared spongy zinc, it would be possible to give up the use of the additions hitherto employed.

20 The following are examples of how this invention can be carried into effect, but we do not limit ourselves to these examples.

Example 1: Sulfurous acid is passed into 25 a quantity of moist electrolytically prepared spongy zinc containing 100 kilograms of metallic zinc under 300 liters of water, while being well stirred and cooled, until the zinc has for the greater part disappeared. The zinc hydrosulfite solution obtained is 30 decomposed by means of a suitable alkali salt, for instance sodium carbonate, and filtered. A highly concentrated solution of sodium hydrosulfite is thus obtained.

Example 2: 152 kilograms of sodium bisulfite-formaldehyde ($\text{NaHSO}_3 \cdot \text{CH}_2\text{O.H}_2\text{O}$) 35 dissolved in from 200, to 250, kilograms of water are stirred with a quantity of moist electrolytically prepared spongy zinc containing 100 kilograms of metallic zinc and 40 well boiled for from 1 to 2 hours while being stirred. The solution filtered off from zinc sludge contains from 130 to 140 kilograms of sodium formaldehyde-sulfoxylate. By 45 evaporating at low temperature, preferably in *vacuo*, the solid salt is obtained.

Example 3: A solution of 306 kilograms of sodium hydrosulfite formaldehyde in 550 liters of water is stirred with a quantity of moist spongy zinc, electrolytically prepared 50 and containing 100 kilograms of zinc and boiled for from 1, to 2, hours while stirring.

The filtered solution contains from 280, to 290, kilograms of sodium formaldehyde-sulfoxylate.

We claim:

1. The process of reducing sulfurous acid compounds which comprises subjecting the same to the reducing action of spongy electrolytically prepared zinc.

2. The process of reducing sulfurous acid 60 and its salts which comprises subjecting the same to the reducing action of spongy electrolytically prepared zinc to form zinc hydrosulfite, converting the zinc hydrosulfite into alkali hydrosulfite, and further reducing the alkali hydrosulfite in the form of alkali-hydrosulfite-formaldehyde by spongy zinc to form alkali formaldehyde-sulfoxylate.

3. The process of producing hydrosulfurous acid compounds from sulfurous acid compounds which comprises reducing such sulfurous acid compounds by means of spongy zinc.

4. The process of producing alkali formaldehyde-sulfoxylate which comprises reducing an alkali-formaldehyde-bisulfite by means of spongy zinc electrolytically prepared.

5. The process of producing alkali formaldehyde-sulfoxylate which comprises reducing an alkali-formaldehyde hydrosulfite by means of spongy zinc electrolytically prepared.

6. The process of producing sodium-formaldehyde sulfoxylate which comprises reducing sodium-formaldehyde-bisulfite by means of spongy zinc electrolytically prepared.

7. The process of producing sodium-formaldehyde-sulfoxylate which comprises reducing sodium hydrosulfite-formaldehyde by means of spongy zinc electrolytically prepared.

In testimony whereof we have signed our 95 names to this specification in the presence of two subscribing witnesses.

HEINRICH SPECKETER.
EDUARD MARBURG.
